L. P. DENNY

HOUR GLASS

Filed Aug. 19, 1926

UNITED STATES PATENT OFFICE.

LEVI P. DENNY, OF BERKELEY, CALIFORNIA.

HOUR GLASS.

Application filed August 19, 1926. Serial No. 130,173.

My invention relates to improvements in hour glasses, and it consists in the combinations, constructions, and arrangements, hereinafter described and claimed.

5 An object of my invention is to provide an hour glass which is constructed so as to be readily secured to a telephone.

10 A further object of my invention is to provide a device of the type described which is extremely simple in construction and which provides novel means for accurately timing a telephone conversation.

15 Other objects and advantages will appear in the following specification and the novel features of the device will be particularly pointed out in the appended claims.

20 My invention is illustrated in the accompanying drawing, forming a part of this application, in which:

25 Figure 1 is a sectional view through the device showing it operatively applied to a telephone,

Figure 2 is a side elevation of the device,

30 Figure 3 is a vertical section of a modified form of the device, and

Figure 4 is an enlarged detail of a portion of the device shown in Figure 3.

35 In carrying out my invention, I make use of a telephone indicated generally at 1 to which I secure a bracket 2. The bracket 2 has two semi-circular arms 3 and 4 which are adapted to be clamped around the head piece 5 of the telephone and secured to each other by means of a bolt 6.

40 The bracket 2 has two uprights 7 and 8, each of which carries a trunnion. The trunnions 9 and 10 are receivable in openings 11 and 12 in a casing 13. Figure 2 clearly shows how the casing 13 is cylindrical in shape and has cut-away portions 14 and 15 for permitting the hour glass 16 to be viewed.

45 The hour glass 16 is secured in place by end plates 17 and 18, these plates in turn being secured in place in the casing 13. Any predetermined quantity of sand may be disposed in the hour glass 16 for determining different periods of time. From the foregoing description of the various parts of the device, the operation thereof may be readily understood.

50 The device is constructed so as to be especially adapted for long distance telephoning. The time period of three minutes is usually allotted to a telephone conversation between different points before an additional charge

55 is made. A sufficient quantity of sand or

other suitable material is placed in the glass 16 to have this quantity pass from the upper compartment to the lower compartment in three minutes.

The upright 8 is provided with a projection 19, which cooperates with depressions 20 for yieldingly holding the casing 13 in vertical position. When the sand 21 is entirely received in the lower compartment, and it is desired to again operate the device, it is merely necessary to manually swing the casing 13 about the trunnions 9 and 10 as a pivot until the projection 19 is received in the next depression 20. The lower compartment now becomes the upper compartment and the sand will flow into the lower compartment, formerly the upper compartment, thus marking off another period of time of three minutes duration. It is obvious that the quantity of sand may be changed so as to vary the time and period without departing from the spirit and scope of my invention.

In Figures 3 and 4, I show a modified form of the device in which a liquid is made use of for actuating the time indicating mechanism. A casing 50 is secured to the telephone 5 by means of clamps 51. A plunger 52 is mounted in the casing 50 and has openings 53 therein. These openings are large enough to permit the plunger to be moved rapidly downwardly against the tension of a spring 54, when operating the device. Flap valves 55, having small openings 56 therein, permit the liquid 57 to pass slowly therethrough as the spring 54 forces the plunger 52 upwardly. The plunger 52 has a guide rod 57, and this rod is graduated as shown in Figure 4. In Figure 4, I have shown the graduation as being divided into minutes as at 58. In operation, the knob 59 is manually moved downwardly, causing the liquid to pass above the plunger 52. The spring 54 now returns the plunger back to normal position, and in doing so, moves the guide rod 57 upwardly, the guide rod in turn indicating the elapsed time of the telephone conversation.

Figure 3 clearly shows where the guide rod 57 is hollow and is internally threaded for receiving a needle valve 60. This needle valve is an auxiliary control for accurately timing the movement of the plunger 52. The needle valve 60 controls the flow of the liquid through a bore 61 and openings 62. If it is found necessary to permit the guide rod 57 to move more rapidly, it is merely required

to turn the knob 59 to adjust the amount of flow of the liquid through the openings 62 and the bore 61.

I claim:

- 5 1. A device of the type described, comprising a casing, means for removably securing said casing to a telephone, a spring pressed plunger slidably disposed in said casing, a medium carried by said casing, means carried by said plunger for permitting a more rapid movement of said plunger in one direction than in the other, and a guide rod for said plunger, said guide rod being graduated for indicating time.
- 10 15 2. A timing device comprising a casing, a plunger disposed in said casing, means nor-

mally urging said plunger in one direction within said casing, a medium carried by said casing, means carried by said plunger permitting a more rapid movement of the same ²⁰ in one direction than in the other, and a guide rod for said plunger, said guide rod being graduated for indicating time.

3. A timing device comprising a casing, a plunger slidably disposed in said casing, means normally urging said plunger in one direction, said plunger being perforated, and a guide rod for said plunger, said guide rod being graduated for indicating time.

In testimony whereof I affix my signature.

LEVI P. DENNY.
